Hyatt G. Soules

United States Patent Office.

HIRAM G. SOULES, OF SYRACUSE, NEW YORK.

Letters Patent No. 91,577, dated June 22, 1869.

IMPROVED MACHINE FOR MANUFACTURING ROOFING.

The Schedule referred to in these Letters Patent and making part of the same.

To all whom it may concern:

Be it known that I, HIRAM G. SOULES, of Syracuse, in the county of Onondaga, and State of New York, have invented a new and improved Roofing-Machine; and I do hereby declare that the following is a full, clear, and exact description thereof, which will enable those skilled in the art to make and use the same, reference being had to the accompanying drawings, forming part of this specification, in which—

Figure 1 is a side view of my invention;

Figure 2 is a plan view of the roller and frame; and

Figure 3 is a front view of the rolling-bed.

Similar letters of reference indicate like parts in all the figures.

This invention relates to certain new and useful improvements in the method and apparatus for preparing composition-roofing, whereby a cheap and efficient apparatus is obtained, and the work done in an expeditious manner, as hereinafter more fully described.

In the accompanying drawings—

A is the bed on which the roofing is prepared, and *a a* is the track, or rails.

B is the spreading-roller, and C the sand-box.

The roofing is prepared as follows:

A piece of felting is laid upon the bed A, between the rails *a a*, as shown by fig. 3, and the hot composition is distributed along on the upper surface of the felting, by a dipper, as usual, or by other suitable means. The hot roller B is then rolled over the track *a a*, and spreads the tar or composition evenly over the surface of the felt. As the spreading-roller B passes over the felt, it is followed by the sand-box C, which sprinkles sand on the warm composition, and gives its upper surface the proper hard finish. The prepared roofing is then removed as soon as it has cooled sufficiently, and another piece prepared in the same manner.

The sand-box C is supported in the roller-frame *b*, and has a narrow opening in its bottom, which is closed by a valve, or cover, *c*, fig. 1, said valve being operated by a hand-lever, *f*, so that the sand is let on and shut off, as required, and by these means the sand-finish is distributed to the composition with the greatest facility.

One side of the roller-frame *b*, fig. 2, has a hinge-joint at *g*, so that the frame can be opened for taking out a cold roller, B, and taking in a hot one in its stead.

The joint *g* is held rigidly in a closed position by a cam-lever, *h*, but the frame is free to be opened when the cam-lever is in a raised position.

i represents a curved shield, extending forward from the sand-hopper C, and overhanging the roller B. Its object is to protect the operator from the effect of the heat radiating from the roller B.

The spreading-roller B can have flanges on its ends, to guide it along the rails *a*, or can be used without them, as desired.

In laying the felting E, fig. 3, between the rails *a*, one edge, *e*, is turned under two or three inches, so as to not receive any of the composition or coating, and when the roofing is to be laid, this blank edge *e* serves to cement the sheets together, so that the use of narrow blank strips of felting, for that purpose, is not necessary, as is usually the case.

A fixed cylinder or scraper can be used in the place of the spreading-roller B, but the roller is preferable, as it works more freely.

In an ordinary apparatus, where the roofing is prepared on a bed, A, between rails *a a*, the composition is poured upon a bed of sand, and the felting laid over all, but in the present method the composition is laid on uppermost, and so exposed that it cools readily, and the sand is distributed in such manner that the trouble of preparing the sand-bed for each sheet, as heretofore, is avoided.

I am aware of the patent granted to W. R. Coe, dated August 14, 1866, but as his invention forms no part of mine, I do not wish to claim it.

Having thus described my invention,

What I claim as new, and desire to secure by Letters Patent, is—

The roofing-machine herein described, consisting of the open frame, with its jointed side *b g*, and fastening *h*, the detachable roller B, and sand-hopper C, having the shield *i* and the pivoted gate *c*, operated by means of lever *f*, the frame being provided with a suitable handle, and all the parts constructed and arranged to operate substantially as herein described, for the purpose of preparing roofing, as set forth.

The above specification of my invention signed by me, this 13th day of March, 1869.

HIRAM G. SOULES.
